EMBROIDERED REINFORCED ROD POCKET
FOR CURTAINS

Samuel Brand, New York, N. Y.

Application February 15, 1935, Serial No. 6,675

5 Claims. (Cl. 156—10)

This invention relates to new and useful improvements in a process for manufacturing embroidered reenforced rod pockets for curtains and the like, and to the said articles.

5 The invention has for an object the teaching of a process by which descriptive tapes are stitched down upon the curtain material and arranged into various designs, which designs include spaced loops of the tape material so that 10 the material of the curtain within the loops may be cut for producing a rod pocket.

A still further object of the invention is the construction of embroidered reenforced rod pockets for curtains which are constructed by ornamental tape stitched down on the curtains and formed with loops in which the material of the curtain is cut to form the pockets.

The invention contemplates the application of this invention to plain top curtains and curtains 20 having hems. With the construction described in the previous paragraphs, the materials of the curtains must be engaged to the front and to the back of the supporting rods.

As a further object, the invention contemplates the provision of extensions from the sewed down loops adapted to engage the rods in such a manner that the rods may be located completely behind the curtains.

Another object of the invention is the construction of an article as mentioned which is simple and durable and which can be manufactured and sold at a reasonable cost.

For further comprehension of the invention, and of the objects and advantages thereof, reference will be had to the following description and accompanying drawing, and to the appended claims in which the various novel features are more particularly set forth.

In the accompanying drawing forming a material part of this disclosure:

40 Fig. 1 is a front elevational view of a curtain constructed according to this invention.

Fig. 2 is a fragmentary enlarged detailed view of one corner of the curtain shown in Fig. 1 applied upon a rod.

Fig. 3 is a plan view of Fig. 2.

Fig. 4 is a fragmentary end elevational view looking in the direction of the line 4—4 of Fig. 3.

Fig. 5 is a front elevational view of a curtain 50 constructed according to a modification of the invention.

Fig. 6 is a fragmentary enlarged detailed view of the upper left hand corner of Fig. 7.

Fig. 7 is a fragmentary enlarged sectional view 55 taken on the line 7—7 of Fig. 6.

Fig. 8 is a fragmentary enlarged view of a curtain constructed according to a modification of the invention.

Fig. 9 is a sectional view taken on the line 9—9 of Fig. 8.

In Figs. 1—4 inclusive, a curtain 10 of lace or other material is shown provided with ornamental embroidery in the form of tapes 11 and 12 stitched in fixed positions and extended along the top thereof. The tape 11 is formed into a plurality of vertical loops 11^a arranged in closely spaced pairs. The material of the curtain 10 within the loops 11^a is cut or punctured so as to form passages for the curtain rod 13. The upper edge of the curtain will zigzag to the front and back of the curtain 15 rod, as clearly illustrated in Fig. 3, producing a plurality of folds 10' at the top. The tape 12 extends straight across the upper ends of the loops 11^a. The tapes 11 and 12 are secured in fixed positions by stitches 14 which engage through the 20 tapes and through the material of the curtain.

A feature of the invention resides in the fact that the tapes 11 and 12 constitute embroidery ornamentation for the curtain in addition to constituting reinforcements for the openings through 25 which the rod passes. The upper ends of the loops 11^a will rest upon the rod 13, and these portions of the loops are reenforced by the tape 12.

In Figs. 5 to 7 inclusive, another embodiment 30 of the invention has been disclosed which is applied to a curtain 10^a. This curtain is formed with a hem 10^b in the top. The hem 10^b is secured down by a top line of stitches 15 and a bottom line of stitches 16. Tape material 11^b and 12^a are secured down upon the material of the hem and 35 extend along the top edge of the curtain. The tape 11^b is arranged with a plurality of pairs of loops 11^c. The tape 12^a extends across the tops of the loops 11^c. Between each pair of loops 11^c the tapes 11^b and 12^a come together and meet, and 40 are covered by small circular ornaments 17.

The material of the curtain within the loops 11^c is cut to form openings for the curtain rod. The tapes 11^b and 12^a are secured down by stitches 14 engaging through the tapes and the material of 45 the curtain. The tape 11^b is one continuous piece and the loops 11^c are formed merely by properly bending and extending the tape.

In Figs. 8 and 9 another embodiment of the invention has been disclosed in which the curtain 50 10 is provided with tapes 11^d and 12^d extended along the tops thereof. The tape 11^d is formed into a plurality of loop portions 19. The tape 12^d extends across the tops of the loop portions. Each of the loop portions 19 consist of several 55

turns, including a small turn 18* which is free. The other turns of the loops 18 are sewed down, as previously described, by stitches. The free turn 18* is adapted to be extended through the opening which is cut in the material within the center of each loop, to the rear. The turn 18* constitutes a loop by which the curtain may be supported. The feature of this invention resides in the fact that with this construction there is a possible selection of the manner in which the curtain is to be supported. The curtain rod will be passed through the openings within the loops 18, or will be passed through the loops 18*.

While I have illustrated and described the preferred embodiment of my invention it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patents is:

1. An embroidered reenforced rod pocket for curtains and the like, comprising curtain material, embroidered material secured down upon said curtain material and including loops, and the material of the curtain being cut in said loops forming rod pocket openings.

2. An embroidered reenforced rod pocket for curtains and the like, comprising curtain material,

embroidered material secured down upon said curtain material and including loops, and the material of the curtain being cut in said loops forming rod pocket openings, said loops being arranged in spaced pairs.

3. An embroidered reenforced rod pocket for curtains and the like, comprising curtain material, embroidered material secured down upon said curtain material and including loops, and the material of the curtains being cut in said loops forming rod pocket openings, said embroidered material comprising tapes, one of said tapes being bent and formed into a plurality of spaced pairs of loops, and other of said tapes being extended across the tops of said loops.

4. An embroidered reenforced rod pocket for curtains, comprising a curtain having a top hem, embroidered material attached upon said hem and formed to include a plurality of loops, and the material of the hem and curtain being cut within said loops for the passage of curtain support rods.

5. An embroidered reenforced rod pocket for curtains, comprising curtain material, embroidered material secured thereon and including a tape arranged in the form of a plurality of spaced loops, said tape having one free turn at each loop, the material of the curtain being cut in the loops and said free turns being engaged through the openings to the rear face of the curtain.

SAMUEL BRAND. 30
